J. H. DICKINSON

SOUND BOX FOR SOUND REPRODUCING MACHINES

Filed Dec. 16, 1919

UNITED STATES PATENT OFFICE.

JOSEPH HUNTER DICKINSON, OF LARCHMONT, NEW YORK, ASSIGNOR TO THE AEOLIAN COMPANY, A CORPORATION OF CONNECTICUT.

SOUND BOX FOR SOUND-REPRODUCING MACHINES.

Application filed December 16, 1919. Serial No. 345,210.

To all whom it may concern:

Be it known that I, JOSEPH H. DICKINSON, a citizen of the United States of America, residing at Larchmont, Westchester County, 5 New York, have invented certain new and useful Improvements in Sound Boxes for Sound-Reproducing Machines, of which the following is a specification.

My present invention relates to improvements in sound-boxes and more particularly to a sound-box provided with means readily controllable by the operator for adjusting the effective size of the diaphragm, my improvement being a very useful one because 10 the various instruments and voices are best reproduced by certain sizes of diaphragms to the exclusion of other sizes.

The annexed drawings show only one of the preferred forms my invention is adapted 20 to take. In them, Fig. 1 is a face-view of a sound-box within my invention, partly broken away to reveal the inside structure; Fig. 2 is a sectional view partly in elevation on the line 2—2 in Fig. 1 looking in the direction of the arrows; Fig. 3 is a similar view except that it is on the line 3—3 in said Fig. 1; Fig. 5 is also a similar view but on the line 5—5 in Fig. 1; and Fig. 4 is a rear view of the sound-box of Fig. 1.

30 Describing now the devices of the drawings, the illustrated sound-box comprises a cup-shaped body-portion 1, a diaphragm 2, stylus-bar 3 pivotally supported at 4 on lugs 5 integral with said body of the box, said 35 stylus-bar having the usual foot 3^a secured to the center of the diaphragm.

On opposite sides of the diaphragm are a pair of rotatable rings 6 and 7 respectively carrying gaskets 8 and 9 on their faces next 40 to the diaphragm, those shown being intended preferably to be rubber-gaskets, one of large diameter, the other of small diameter, cemented in annular grooves provided for the purpose in the faces of the aforesaid rings. 45 These rings 6 and 7 have screw-threaded engagement with the body of the box at 10 and 11 respectively, the threads running in the same direction.

Each ring 6 and 7 has a rigid lug 12 projecting laterally from it away from the diaphragm. The lug 12 on the ring 7 projects through an arc-shaped opening 13 in the back of the sound-box; and the lug 12 on the other ring 6 similarly projects through 55 an arc-shaped opening 14 in the front 15,

the latter consisting of a ring-shaped plate (whose cross-section is shown in Figs. 2, 3 and 5) secured by screws 16 to the mouth of the body 1 of the sound-box. 17 is a U-shaped yoke having finger-piece 17^a, said 60 yoke rigidly uniting the aforesaid lugs 12—12 and the screw-rings 6 and 7, whereby adjusting the finger-piece and yoke 17 circumferentially of the sound-box in either direction (permitted by the arc-shaped slots 65 13 and 14) will similarly rotate the screw-rings 6 and 7 and will at the same time adjust them laterally relatively to the diaphragm 2, but in opposite directions,—that is to say, as one screw-ring approaches the 70 diaphragm, the other will recede from it.

Opposed to the gasket 8 on the screw-ring 6 is a stationary gasket 18 cemented to the body of the box as shown. Also opposed to the gasket 9 on the other screw-ring 7 is a 75 gasket 19 cemented as shown to the front-plate 15 of the sound-box.

Figs. 2 and 3 show the different results of adjusting the finger and yoke 17 in opposite directions. Thus, in Fig. 2, the screw-ring 80 6 has carried its gasket 8 to the right and has forced the diaphragm over against the stationary gasket 18, the two gaskets gripping the diaphragm between them. This same movement has taken the diaphragm 85 out of contact with the smaller stationary gasket 19. Thus, in Fig. 2, the full size of the diaphragm is effective or in play.

In Fig. 3, there has been a reverse adjustment of the parts, reducing the effective size of the diaphragm to that contained within the small gaskets 9—19. In this figure, the adjustment has carried the ring 7 and its gasket 9 to the left and has forced the diaphragm over against the stationary 95 gasket 19, and at the same time (compare Fig. 2) has carried the diaphragm away from contact with the gasket 18. This latter eliminates the buzzing noises which might occur if the diaphragm remained in 100 contact with the gasket 18 in Fig. 3. The same applies to the gasket 19 in Fig. 2.

The reason why adjusting the yoke 17 takes the diaphragm out of contact with the said gasket 18 in Fig. 3 (and out of contact 105 with said gasket 19 in Fig. 2) is that the net lateral distance between said two stationary gaskets is made greater than the thickness of the diaphragm.

Similarly, the net lateral distance between 110

the two adjustable or screw-ring gaskets 8 and 9 is purposely made greater than the thickness of the diaphragm, so that whichever is not gripping the diaphragm (viz: 9 in Fig. 2 and 8 in Fig. 3) is out of contact therewith and therefore cannot result in buzzing or other noises.

I preferably provide means for preventing rotary displacement of the diaphragm 10 without interfering with its slight lateral displacement as described above. The means shown for this purpose consists of an integral tongue or tongues 2^a (Figs. 1, 4 and 5) projecting outwardly from the periphery of 15 the diaphragm and seated in recesses 1^a provided for the purpose in the body of the sound-box.

Of course, it is conceivable that the gasket instead of being made as preferred of rubber might consist of mere ridges or the like 20 on the screw-rings 6 and 7 or on the parts 1 and 15. Also other changes and modifications might be made both in the materials used and in the preferred construction as 25 shown and described which nevertheless will still be within the spirit of this inventive disclosure and these I mean to be covered by the annexed claims.

What I claim is:

30 1. The combination with a sound-box and its diaphragm, of a gasket-member laterally adjustable to and from one side of said diaphragm, another gasket-member of different diameter adjustable to and from the other 35 side of said diaphragm, and means in common for oppositely adjusting both gasket-members so that when either is against the diaphragm, the other is removed from it.

2. The combination with a sound-box and 40 its diaphragm, of a gasket-member laterally adjustable to and from one side of said diaphragm, another gasket-member of different diameter adjustable to and from the other 45 side of said diaphragm, and means in common for oppositely adjusting both gasket-members so that when either is against the diaphragm, the other is removed from it; stationary gasket-members opposed to the adjustable gasket-members, one opposite 50 each adjustable gasket-member on the other side of the diaphragm.

3. The combination with a sound-box and 55 its diaphragm, of a gasket-member laterally adjustable to and from one side of said diaphragm, another gasket-member of different diameter adjustable to and from the other side of said diaphragm, and means in common for oppositely adjusting both gasket-members so that when either is against the 60 diaphragm, the other is removed from it; stationary gasket-members opposed to the adjustable gasket-members, one opposite each adjustable gasket-member on the other side of the diaphragm; the lateral distance 65 between the said stationary gasket-members

being a little greater than the thickness of the diaphragm, as is also the lateral distance between the adjustable gasket-members.

4. The combination with a sound box and 70 its diaphragm, of pairs of gasket members of relatively different diameters, one member of each pair being laterally adjustable to engage and disengage relatively to a side of the diaphragm, and means for moving one of said adjustable gasket members into engagement with the diaphragm and concurrently moving the other adjustable gasket member in a direction away from the diaphragm.

5. The combination with a sound-box and 80 its diaphragm, of a ring provided with a gasket-member at one side of the diaphragm, and having screw-threaded engagement with the sound-box so that turning the ring in one direction or the other adjusts the gasket-member to or from the diaphragm, another ring on the opposite side of the diaphragm having a different diametered gasket-member 85 from the first-named gasket-member, and also having screw-threaded engagement with the sound-box so that turning said ring in one direction or the other adjusts its gasket-member to or from said diaphragm, both of said rings being screw-threaded in the same direction; and a finger-piece 90 attached to both rings for effecting the simultaneous adjustment in opposite directions of said rings and gasket-members.

6. The combination with a sound-box and 95 its diaphragm, of a ring provided with a 100 gasket-member at one side of the diaphragm, and having screw-threaded engagement with the sound-box so that turning the ring in one direction or the other adjusts the gasket-member to or from the diaphragm, another ring on the opposite side of the diaphragm having a different diametered gasket-member 105 from the first named gasket-member, and also having screw-threaded engagement with the sound-box so that turning said ring in one direction or the other adjusts its gasket-member to or from said diaphragm, both of said rings being screw-threaded in the same direction; a finger-piece 110 attached to both rings for effecting the simultaneous adjustment in opposite directions of said rings and gasket-members; and stationary gasket-members opposed to the 115 adjustable gasket-members, one opposite each adjustable gasket-member on the other side of the diaphragm.

7. The combination with a sound-box and 120 its diaphragm, of a ring provided with a gasket-member at one side of the diaphragm, and having screw-threaded engagement with 125 the sound-box so that turning the ring in one direction or the other adjusts the gasket-member to or from the diaphragm, another ring on the opposite side of the diaphragm having a different diametered gasket-member 130

- from the first named gasket-member, and also having screw-threaded engagement with the sound-box so that turning said ring in one direction or the other adjusts its 5 gasket-member to or from said diaphragm, both of said rings being screw-threaded in the same direction; a finger-piece attached to both rings for effecting the simultaneous adjustment in opposite directions of said 10 rings and gasket-members; and stationary gasket-members opposed to the adjustable gasket-members, one opposite each adjustable gasket-member on the other side of the diaphragm; the lateral distance between the 15 stationary gasket-members being a little greater than the thickness of the diaphragm, as is also the lateral distance between the gasket-members on the adjustable rings.
8. The combination with a sound-box and 20 a diaphragm, therein the peripheral edge of which is capable of lateral displacement relatively to the sound box, of a ring provided with a gasket-member at one side of the
- diaphragm and having screw-threaded engagement with the sound-box so that turning the ring in one direction or the other, 25 adjusts the gasket-member to or from the diaphragm, an opposed gasket-member on the opposite side of the diaphragm, and means at the periphery of the diaphragm 30 preventing it from turning although permitting lateral displacement thereof.
9. The combination with a sound-box and its diaphragm, of a plurality of pairs of opposed gasket-members for engaging said 35 diaphragm at different distances from its center; and means for selectively adjusting the gasket-members laterally to and from said diaphragm to cause one pair of gasket members to clamp the diaphragm and another pair of gasket members to disengage 40 from the diaphragm.

In testimony whereof, I have signed my name to this specification this 15th day of December, 1919.

JOSEPH HUNTER DICKINSON.
